UNITED STATES PATENT OFFICE.

WILLIAM H. KNOWLES, OF HARTFORD, CONNECTICUT.

AUTOMATIC RECOIL-OPERATIVE FIREARM.

No. 829,163.

Specification of Letters Patent.

Patented Aug. 21, 1906.

Application filed May 18, 1905. Serial No. 261,265.

To all whom it may concern:

Be it known that I, WILLIAM H. KNOWLES, a citizen of the United States of America, and a resident of Hartford, in the county of Hartford and State of Connecticut, have invented certain new and useful Improvements in Automatic Recoil-Operative Firearms, of which the following is a full, clear, and exact description:

10 This invention relates to machine-guns and analogous firearms in which the successive operations of loading and firing are made to rapidly occur at the will of the operator by recoil-operated means included in the mechanism of the firearm.

15 A principal object of this invention is to provide in a gun of this class improved recoil-operated means for automatically "feeding in" the belt-carried cartridge ammunition and for the transferring of the cartridges successively from the belt to the cartridge-chamber in the barrel and also to provide novel and improved means coacting with the cartridge-feeding means for extracting 25 and ejecting the exploded cartridge-shells.

20 Another object is to provide an entirely new and reorganized system of firing mechanism including a firing-pin-engaging sear and simple and reliable devices which control the operations thereof.

25 Another object is to provide a machine-gun of the class described comprising a minimum number of parts, the individual form and character of which are such as to well withstand the wear and strain to which 30 they are subjected and which present no difficulties in their manufacture and assemblage.

35 Another important feature of this invention lies in the peculiar construction of the frame and rear closure-block or butt-piece for the same which admit of a novel manner of assembling or dismounting all of the frame-contained parts without the employment of 40 any special tools or implements, the maintenance of the assembled parts of the arm in their respective and coöperative positions being accomplished without the requirement of screws or other fastening means, such as 45 50 have heretofore been necessary.

The more prominent features of invention included in this firearm are found in or constituted by the cartridge-belt-feeding device and recoil-actuated means for operating it; 55 provisions on or appurtenant to the barrel and operating in conjunction with a peculiar

formation of the frame for withdrawing the cartridges successively from the cartridge-belt and insuring their positioning to be engaged by the breech-piece, this means contributing in large measure in the operation of extraction and ejection of the empty shells; the combination of barrel-receiver, breech-piece, and firing-pin, which combined parts have formations and coactions for automatically and in proper time locking the breech-piece within the receiver for the required concurrent movements of said parts and for the unlocking of such parts for their required independent movements; the combination with the firing-pin contained within and movable relatively to the receiver-inclosed breech-piece of the sear and a controlling means for the sear; new means for initially putting the parts of the action into condition for continuous rapid or intermittent firing; the combination, with the coacting firing-pin and sear, of a trip-rod recoil-operated and controlling the sear so that after its each discharge the firearm assumes a cocked condition, together with the further combination therewith of a firing-button to be controlled by the thumb and for assuring, according to the pressure or release on said button, the successive rapid loadings and discharges of the gun or the suspension of such operation, and the general combination or organization and arrangement of the parts for their conjoint operations and results, as particularly shown in the drawings definitely described herein-after.

In the accompanying drawings, Figure 1 is a side elevation of the improved firearm. Fig. 2 is a perspective view of the butt portion of the same. Fig. 3 is a perspective view of the rear portion of the frame, showing certain new structural formations, to be hereinafter particularly referred to. Fig. 4 is a perspective view of the butt-block or "butt-piece." Fig. 5 is a perspective view of the trip-rod. Fig. 6 is a perspective view of the parts of the device shown in separated relations having coöperative locking arrangements with the trip-rod and butt-block. Fig. 6^a is a sectional view as taken on line 6^a 6^a, Fig. 20, through a part of the receiver and rib thereon in relation to the head of a cartridge for making clear a structural feature hereinafter more particularly referred to. Fig. 7 is a longitudinal section through the firing-arm, taken on the plane indicated by the line y y, Fig. 2, and also on the cross-sec-

tional view, Fig. 16. Fig. 8 is a longitudinal sectional view of the firearm, taken on the plane represented by the line $x\ x$, Figs. 2 and 16. Figs. 9, 10, 11, 12, and 13 are cross-sectional views taken, respectively, on the lines 9, 9, 10, 10, 11, 11, 12, 12, and 13, 13 of Fig. 8, all as seen looking toward the rear of the firearm. Fig. 14 is substantially a longitudinal sectional view as taken on the plane $x\ x$, the same as Fig. 8, but showing the parts in their relations as assumed instantly following the discharge and recoil of the gun. Fig. 15 is a view substantially similar to Fig. 14 with the parts taken in section on the same plane, but showing the relations of the parts as assumed at a slightly-later instant in the operation of the gun from those assumed in Fig. 14. Fig. 16 is a cross-sectional view on line 16, 16, Fig. 8, as seen looking in a forward direction. Fig. 17 is a perspective view of a hook-retaining spring to be hereinafter more definitely referred to. Fig. 18 is a perspective view of a detent for the cartridge-belt, which has an intermittent feed movement transversely of the firearm. Fig. 19 is a perspective view of the cartridge-feeding hook-rod, shown in its relation to a portion of the barrel-receiver. Fig. 20 is a perspective view showing a portion of the barrel, the barrel-receiver, the breech-piece, and firing-pin and equipments of said parts. Fig. 21 is a perspective view of a portion of the firing-pin. Fig. 22 is a perspective view of the breech-piece. Fig. 23 is a plan view of a rear portion of the breech-piece, together with a portion of the firing-pin. Figs. 24 and 25 are vertical longitudinal sectional views, on a considerably-enlarged scale, of the firing mechanism, located at the butt portion of the gun, and showing the parts in different positions in the different views.

In the drawings the frame A, which is of considerable length relative to its diameter, has centrally located in the lower cylindrical portion thereof and extending longitudinally therethrough the hole or bore A'. This bore is suitably counterbored and shouldered for the accommodation of various parts, to be hereinafter described. The forward end of the bore A' is carried somewhat beyond the forward end of the frame proper in the barrel-supporting extension A² and is at this point of reduced diameter and forms a closely-fitting bearing for the sliding barrel B.

The barrel B, which usually has a rifled bore and a cartridge-chamber at its breech end, is screw-connected by its said breech end to a receiver C, this receiver being, in fact, a rear extension of the barrel and is in substance the same as an integral part thereof. The cylindrical body of the receiver C is of slightly-greater diameter than that of barrel B and has centrally located therein and extending longitudinally there-

through a hole or bore 2. A mortise-like

opening 3, somewhat longer than the cartridge used in the arm and of a width equal to diameter of bore 2, is formed in the top portion of the receiver. Directly below and in line with this opening 3 is a similar opening 4, (of a width somewhat less than the bore 2,) formed in the lower portion of said receiver. At the forward end portion of these openings 3 and 4 are diagonally oppositely located angularly-extending rabbets 75 or cuts 5, 5, both thereof being indicated in Fig. 20 and also in Fig. 10.

The forward cylindrical end portion of the receiver-body C, adjacent its juncture with barrel B, has provided thereon an upwardly-extending and downwardly and rearwardly inclined recessed or notched projection or lug 6, Figs. 8, 19 and 20. The corresponding cylindrical rear portion of the receiver has formed as one therewith or secured thereon the rib-like cam 7, the cam edge of which extends from a point over the forward end of the mortise 3 rearwardly and downwardly to a point near the rear end of said mortise, all as clearly shown in Figs. 8, 11, 14, 15, and 20. Within the receiver C and fitted to slide longitudinally in the bore 2 thereof is the sliding breech-piece G. The forward end of this breech-piece G has a notched or recessed cross-head I, on the forward end face of which are formed the slides 9, 9, which are of a form to fit and engage the cannelured head of a cartridge. This breech-piece G is bored from its rear end longitudinally to a point adjacent its front end for the reception of the straight cylindrical portion of the firing-pin H, which has a sliding engagement in as well as another manner of engagement therewith. This firing-pin H at its rear end portion is of an enlarged diameter equal to the bore 2 of the receiver, its forward portion being of a somewhat reduced diameter—that is, of a diameter equal to the above-described bore in the breech-piece G.

The forward end of the firing-pin terminates in a conical-shaped point, which is received in a similar-shaped end formation in the bore 10 of the breech-piece. This conical end in the bore 10 has a small hole 12 centrally provided therein and centrally of the face of breech-piece head I, through which the point of the firing-pin H projects. The extreme rear end of the firing-pin has formed thereon a disk-like head 13, this head being partly of a diameter equal to that of the receiver C, but having a portion 14 at its upper edge slightly extended, which fits and has endwise-sliding engagement with a corresponding shallow-grooved portion 15 of the bore A' of the frame A, Figs. 11 and 12, to the end that in its backward and forward sliding movements the firing-pin H is thereby prevented from any rotation within the bore A'.

The breech-piece G, within and relatively

to which the firing-pin H has the endwise movement, has imparted thereto a partial rotation at each forward and rearward movement by the engagement of the lugs *h* on the non-rotatable firing-pin H with the angular or cam portion *g* of the breech-piece slots G', and the diametrically opposite and parallel straight portions *g'* of said slots have also an important function, as will be hereinafter described.

The firing-pin H has a central bore *n* and receives therein a spring M, which abuts by its forward end against the forward end of bore *n*, its rear end being attached to a spring-
15 supporting rod m adjacent the rear end of the latter. The rear end portion of this spring-rod m is of reduced diameter and fits in a hole *m'* of like diameter in the butt-piece O, Figs. 4, 7, and 8, and is maintained in place therein by the rearward pressure of the spring M on said rod.

The rear portion of the frame A is cut away underneath for some little distance from its end, and the side walls of this aperture A³ thus produced have vertically-extending
25 grooves 16 16, Figs. 3 and 13.

The butt-piece O (see Fig. 4) has a cross-sectional shape fitting the cut-away portion A³ of the frame A and has formed on each
30 side thereof the vertically-extending ribs 18 18, which fit into the grooves 16 16 in the side walls of the cut or aperture A³ in frame A, and whereby when the butt-piece O has been inserted in the frame-aperture A³ and
35 pushed vertically upwardly into its place therein a strong and effectual rear closure of the frame is attained.

A suitable handpiece or grip 20 is formed on and integral with the butt-piece O and
40 may have attached thereto the usual cheek-pieces.

The frame A, above the cylindrical lower portion thereof, is reinforced or thickened, as is shown in the various cross-sections of the drawings, and has formed in said reinforced
45 portion various chamber cuts or recesses. These cuts, in which are located important coacting parts of the arm, are arranged in planes relative to the center of the frame-bore A', as indicated by the section-lines x x and y y of Figs. 2 and 16.

A hook-rod K, which constitutes the feeding device for the cartridge-belt, (shown in Figs. 7 and 19,) is supported and guided at
55 its front end portion and has endwise movements in hole or bore 23 in the upper reinforced part of frame A, the rear end of the said rod being also guided in the hole or bore 24 in the butt-piece O. The hook or offset
60 portion 22 of the hook-rod, which is straight and extends parallel with the front end portion of the said rod, is clearly illustrated in Figs. 14, 15, and 19.

An intermediate portion of the hook-rod
65 K, which is over the receiver C when the lat-

ter is in its normal position, is flattened and given a spiral twist, as seen at 21^a, (see Figs. 7 and 19,) and the forward end of said twisted portion terminates in a pronounced shoulder 25, and the flattened and spread portion 21^a of the said rod engages in the recess or notch in lug 6 of the receiver, and at certain periods in the operation of the arm the hook-rod is partially rotated by reason of endwise movements of the receiver relatively to the hook-rod. One important function of this hook-rod K is the support it affords to the spring L of the arm. This spring L, being coiled around the rod, abuts at its rear end against the butt-piece O and exerts a powerful forward pressure on the rear side of the receiver-lug 6, thereby keeping the receiver C and barrel B normally in a forward position in the frame A, and this spring L is for forwardly retracting the barrel after yielding at each
75 recoil and will be herein termed the "barrel-retracting" spring.

For the automatic supplying of cartridges successively to the arm to sustain a rapid fire therefrom the ordinary feed-belt well known
80 in this class of firearms is employed.

The exact manner for automatically delivering the cartridges 26 carried in the belt 27 through the aperture 28 in frame A into and within the arm and the subsequent withdrawal of the cartridges one at a time in succession from the loops 29 of said belt, together with the simultaneous movement of the emptied portion of the belt through the oppositely-located egress-aperture 30, will be
85 later described with particularity in connection with other coacting parts which are instrumental in and contribute to the ammunition-supply feed.

In Fig. 8 of the drawings, which is a longitudinal section of the arm as taken on line x x of Figs. 2 and 16, the cocking and tripping rod or "trip-rod," as it will be termed, is shown at J as supported in the reinforced upper portion of frame A within the hole or bore 31. A flattened or cut-away under side portion of this trip-rod J has terminal shoulders 32 and 33, which are alternately engaged by the lug 34 on cam-rib 7 of the receiver C, this cam-rib being guided and having longitudinal movement in the angularly-inclined slot 35, which slot connects the trip-rod bore 31 with the main bore A' of frame A. (See Figs. 3, 8, 12, &c.) This cam-rib 7, guided in the slot 35, prevents the turning of the barrel and receiver. The rear end portion of the trip-rod is supported and guided within the recess or notch 36 in the butt-piece O and has formed thereon the knurled knob 37, which normally lies within the depression 38, formed in the butt-piece O. A slight endwise movement that is imparted to the trip-rod J by the automatically-actuated engagement of the lug 34 of the cam-rib 7 with the trip-rod shoulders 32 and 33 is provided for by the short
105
110
115
120
125
130

flattened portion 39 of the trip-rod, (see Figs. 5, 6, 7, 8, and 13,) with which a transversely-located spring-pressed stop-bolt 40 engages. This stop-bolt 40, as reference to the above-mentioned figures of the drawings illustrate, slides within a shouldered or counterbored hole 41 in the upper portion of the butt-piece O and has an upwardly-extending pin 42, which protrudes through a transverse slot 43 in the said part O. Provision for easy access to this pin for manipulation is made by the cut-away portions 44 of the frame A. At the opposite or counterbored end of the hole 41 a shouldered fastening-bolt 45 is provided, which engages a hole 41^a in frame A, thereby preventing the butt-piece O from dropping downward from its assembled position. A spring 46 within hole 41, interposed between the stop-bolt 40 and the fastening-bolt 45, furnishes endwise spring-pressure for both.

In the operation of taking apart of the arm it is a noteworthy fact that as no screws, bolts, or pins are employed in its construction its capability for withstanding rough service and its consequent military value are greatly enhanced, the unlocking operation necessary to permit the dismantling of the piece being the pushing in of the shouldered fastening-bolt 45 from the outside of hole 41^a by means of a piece of wire, a nail, or other small object until the said bolt 45 is entirely within the hole 41 of the butt-piece, at which time a downward pressure on the butt-piece permits of its being entirely removed, and thereafter permitting the rearward withdrawal of the barrel B, the receiver C, the breech-piece, and the firing-pin from the frame A.

The lowering movement of the butt-piece carries the ribs 18 18 thereof below the lower ends of the grooves 16 in the frame, the rod m in this operation being downwardly tilted and offering no obstruction to the disengaging movement of the butt-piece, it being understood that the parts are to be so designed or proportioned that the engaging ribs may become disengaged from the frame before the limit of downward-tilting movement of the rod m is reached, the butt-piece then being free to be drawn away rearwardly.

In the lower portion of the butt-piece O in line with the bore A' of the arm and extending from the rear face thereof nearly through said piece is a hole or bore 48, in which the hollow cylindrical firing-button P is fitted for a slight endwise movement against the rearward pressure of its internal spring 50. An inclined slot 51 in the butt-piece O connects this bore 48 with the trip-rod-supporting recess 36. This slot is forwardly open, connecting with the rear end of the frame-bore A', and is rearwardly closed, as a reference to Figs. 8, 14, and 15 and more especially to the enlarged views Figs. 24 and 25

of the drawings clearly shows. Pivoted supported in the forward portion of this slot 51 is the sear S. A downwardly-extending member 52 thereof extends across the open front end of the firing-button P and receives the forwardly-exerted pressure of the aforesaid spring 50. A forwardly-extending hook 55 of sear S projects within and beyond the slot 51 into the rear portion of the frame-bore A' and in direct line with an aperture 56 in the rearwardly-located flange-like firing-pin head. The upper edge of this aperture 56 is slightly below the normal position of the point of the sear-hook 55, whereby such upper edge of the aperture 56 at a time near the termination of the rearward movement of the firing-pin head 13 encounters the rounded or inclined forward portion of hook 55 and depressing the same slightly against the pressure of spring 50 causes, relatively speaking, the said hook 55 to pass through aperture 56, (this being coincident with the completion of the rearward movement of the firing-pin head 13,) at which time the hook 55 resumes its normal horizontal position, thereby holding the firing-pin in its cocked position, as is clearly shown in Fig. 25 of the drawings.

The upper edge portion of the pivoted sear S has formed therein the rearwardly-open round aperture or socket 60, in which a closely-fitting approximately circular extremity 61 of the triangular sear-operating dog T is engaged. This triangular-shaped dog T is of a thickness but slightly less than that of the slot 51, in which it is movably supported. The normal position of this dog within the slot 51 is as shown in full lines in Fig. 24, with its top side horizontal and its rear rounded corner 62 engaged by the upper portion of a cam depression 63 in the knob 37 of trip-rod J. The lower round-ended extremity 65 of the dog T is closely and positively engaged within the slot 66 in the upper portion of the firing-button P, whereby, as a reference to Fig. 24 illustrates, a pressure on the externally-projecting end of the firing-button carries the corner 65 of dog T forward, drawing corner 62 downward over the forwardly-projecting cam 63 of the knob 37, and thereby carrying the top portion of the dog in a forward direction, which results in swinging the pivoted sear S to the position shown in dotted lines in Fig. 25 of the drawings, and thus by the depressing of hook 55 the firing-pin head 13 is released.

The above-described movements, caused by the pressing of the firing-button, are such as would transpire had the head-piece been previously cocked and the barrel-receiver forwardly returned to its normal position. A prolonged pressure on said firing-button causes the continued recoil-operated automatic loading and firing of the piece by the instrumentality of the coacting parts embod-

ied in the present invention, the operation of which will be described. One end of the belt 27, the loops 29 of which are loaded with cartridges 26, is inserted through the transom-aperture 28 into the chamber 70 of the frame A in a position as shown in Figs. 1 and 8 of the drawings. A small cartridge-retaining spring 71 (shown in position in Fig. 16 and in detail in Fig. 18) permits the belt 27 of cartridges to pass thereunder and into the chamber 70, but prevents any return motion thereof.

The above-described preparatory operation for insuring a continuous supply of cartridges to the arm having been performed, the trip-rod J is released from its retaining engagement with the locking-bolt 40, which is accomplished by the movement toward the right of the locking-bolt pin 42. The trip-rod J is then drawn rearwardly by means of its knob 37.

A reference to Figs. 7 and 8 of the drawings illustrates the various parts of the arm as shown in the positions which they occupy relative to each other previous to the drawing rearward of the trip-rod, and referring particularly to Fig. 8 it will be understood that by reason of the lug 34 on the cam-rib 7 of the receiver being adjacent and to the rear of shoulder 32 of the trip-rod J a resultant rearward movement is imparted thereby to the barrel-receiver C, with its contained breech-piece G and firing-pin H. The limit of this rearward moving of the above-mentioned parts and the position said parts assume on the completion of the same is illustrated in Fig. 14 of the drawings, it being understood that the trip-rod has been pushed forwardly to its place or has been so returned by its engagement with the lug 34, which is to be considered as a part of the receiver, which is always returned to its forward position by the spring L.

Referring now to Figs. 7 and 19 of the drawings, it will be understood that on the commencement of this rearward movement of the receiver C, by the rearward pulling out of the trip-rod J, as described, the hook-rod K, encircled by the barrel-retracting spring L, is carried rearward by the engagement of its spiral-cam portion 21^a within the notched receiver-lug 6 to the lengthwise extent of the butt-piece bore 24, and during this portion of the rearward traveling movement of the receiver any tendency of the hook-rod to rotate axially is resisted by the hook-engaging spring 75, which spring is illustrated in the position it occupies in the arm in Figs. 8, 9, and 16 and in detail in Fig. 17.

The above-described portion of the rearward movement of the receiver C simultaneously performs another important operation of the arm—i. e., a small curved rib 76 on the side of the receiver-lug 6 engages the cannelured head of a cartridge 26 on the feed-

ing into chamber 70 of the latter and on the rearward movement of the receiver operates thereby to draw the cartridge 26 from its loop 29 in belt 27 and to convey it rearwardly. This withdrawal rearwardly of the cartridge is closely followed by the rearward movement of the hook 22 of hook-rod K, to the end that the emptied loop 29 of the belt is entered and engaged by the rear end portion of the hook 22.

Referring to Fig. 14 of the drawings, it will be understood that on the continued rearward movement of receiver C, the hook 22 of rod K having moved to the rearward of its retaining-spring 75, the hook-rod K is rotated by the action between the notched receiver-lug 6 and the flattened spiral-rod portion 21^a, thereby causing the hook 22 to assume the position shown in full lines in said Fig. 14 and indicated by dotted lines in Fig. 85 9, by reason of which rotated position the cartridge-carrying belt 27 is pulled upward and crosswise into the chamber 70, thereby drawing in another cartridge and carrying through the outlet-aperture 30 the emptied portion of the belt 27. This above-described continued rearward movement of receiver C also draws farther rearward the rib-engaged cartridge 26. In this continued or final stage of rearward movement of the said cartridge an overhead inclined cam portion 78 of the chamber 70 deflects the rear end of the cartridge to the position shown in said Fig. 14. The barrel-retracting spring L is at this time compressed, the firing-pin head 13 is engaged by the sear T, the firing-pin spring M is under compression, the trip-rod J is moved slightly rearward by the engagement with its shoulder 33 by the receiver-carried lug 34, and any exploded cartridge-shell that may have been in the barrel B is still in position therein and engaged by the flanges 99 of breech-piece G. As stated in the preceding paragraph, the firing-pin at this time is held rearward by the engagement of the hook member 55 of the sear therewith; but in this case (a prolonged pressure being maintained on the firing-button P) the above-referred-to sear engagement of the firing-pin is produced automatically (instead of manually) by the rearward swinging movement of the top portion of the triangular dog T on its lower or fulcrum point 65, this movement of dog T being directly caused by the swinging movement of the sear S, actuated by the spring pressure on member 52 thereto, as shown in full lines in Fig. 25, which movement of the sear S and the corresponding rearward movement of the top portion of the dog T is permitted by the rearward retirement of the cam-surface 63 of the knob portion of the trip-rod.

At the termination of the previously-described manually-operated rearward withdrawal of the trip-rod and the consequent

drawing rearward from the cartridge-belt of a cartridge 26, the trip-rod J is forced again to its forward position within the frame A. This return in the forward direction of the 5 trip-rod releases the receiver C (by the disengagement of trip-rod shoulder 32 from lug 34 of cam-rib 7) from its rearwardly-held position, as shown in Fig. 14, and retracting-spring L by its engagement with the rear 10 side of receiver-lug 6 immediately carries said receiver and the barrel B forward in the frame A to the position shown in Fig. 15. The breech-piece G within the receiver C is also carried forward a distance nearly equal 15 to the length of the breech-piece slot G' because of the engagement of the breech-piece head I in the angular receiver-recess 5; but during the latter part of this concurrent forward travel of the receiver and breech-piece 20 the angular portions g of said breech-piece slots impart a slight partial rotation to the breech-piece, thus unlocking the head I from the said receiver-recess, and thereby permitting the receiver C and barrel B to complete 25 their forward movement as impelled by the retracting-spring L. The breech-piece G within the receiver C remains held back from an extreme forward movement as imparted 30 to the receiver—that is, it momentarily stays in the position of Fig. 15 by the engagement or binding in the angular portions of 35 the slots g' of the firing-pin lugs h. It will be stated at this point that during the movement of the breech-piece as forwardly carried by the receiver from the position shown in Fig. 14 to the position shown in Fig. 15 the relative action between the inclined slots G' in the tubular body of the receiver and the radial studs h of the firing-pin is 40 effective to partially rotate the breech-piece, so that it is rocked from its position of interlock, as shown in Fig. 10, within the cuts 5 of the receiver, and the longer one of the flanges 9 about concurrent with the unlocking of the breech-piece from the receiver 45 arrives to a position of restraining engagement with the head of the cartridge, so that the forward and downward impingement by the cam 7 will be without effect to forwardly 50 force the cartridge and can have only the action on the latter of crowding it farther downwardly in engagement between the opposite flanges 9 in a direction perpendicular to the axis of the breech-piece.

55 The forwardly-completing movement of the receiver independently of and relatively to the breech-piece of a distance more or less nearly equal to the length of the receiver-mortises 3 and 4 results in the forcing 60 downwardly of the rearwardly-withdrawn cartridge from its deflected position, as seen in Fig. 14, by the engagement therewith of the under cam edge of the receiver-rib 7, and on the continued forward movement of the 65 barrel and receiver to the fully-forward posi-

tion, (shown in Fig. 15,) the said cartridge is forced downward by the downwardly and rearwardly widening cam 7 to a position in line with the bore of the barrel B and with its cannelured head in firm engagement with the opposite flanges or inturned lips 9 of the breech-piece head I.

The rib 76 on the lug 6 of the barrel-receiver C is made, as shown in Fig. 6^a, with a perpendicular or abrupt rear side and a forwardly-beveled front side, so that as the receiver has its forwardly-retracting movement the forwardly-inclined face of the rib 76 can downwardly crowd the cartridge, the forward boundary of the groove being circumferentially less prominent than the shoulder at the rear of the cartridge-head groove. When the cartridge is drawn by the rib 76 rearwardly from the belt to the position shown in Fig. 14, the breech-piece 35 in its partial rotary movement changing from the position of Fig. 10 to the position of Fig. 11, engages the cartridge-head at its one side by its longer end flange 9, (shown at the left in Fig. 10,) the cut-away upper portion 90 of the right-hand flange 9 passing freely under and past the cartridge-head.

Any empty cartridge-shell which may have been in the cartridge-chamber of the barrel and the head of which was engaged 95 by the said flanges 9 of the head I is withdrawn from its position in the barrel during the above-described independent forward movement of the barrel and receiver relatively to the breech-piece and is then crowded downwardly, as shown in Fig. 15 of the drawings, by the cam-depressed fresh cartridge, and thus expelled from its engagement with the said flanges 9.

The final movement of the parts described, 105 resulting in the carrying forward of the fresh cartridge now engaged by the breech-piece head I into the cartridge-chamber of the barrel and the ejecting of the exploded shell from the position shown in full lines in Fig. 15, is brought about by the engagement at this time of lug 34 of the receiver-carried cam-rib 7 with the forward shoulder 32 of the trip-rod which carries said rod forward a slight distance, to the end that the triangular-shaped dog T, having its rear corner 62 in engagement with the lower portion of the cam-surface 63 of the trip-rod knob, is 115 swung forward on its fulcrum-point 65 in the firing-button, and by its sear-engaging corner 61 operates said sear S to depress its hook member 55, and thereby releases and permits of the sudden forward movement of the firing-pin. The first part of this forward movement of the said firing-pin H carries the 125 breech-piece G with it, by reason of the obstruction which the angular portions g of the breech-piece slots present against the firing-pin lugs h. This stage of the forward motion of the breech-piece and firing-pin as one 130

serves to carry the fresh cartridge into the barrel-chamber and, in conjunction with the forward edge of the shell-tripping groove 80 at the rear end of the frame-opening 81, 5 ejects said shell in the manner illustrated in dotted lines in Fig. 15.

Coincident with the seating of the cartridge within the cartridge-chamber of the barrel B the head I of the breech-block G, 10 being unable to move farther forward, is at this time rotated to a locking position with the recessed portions 55 of receiver C by the action of the firing-pin lugs *h h* on the angular portions *g g* of the breech-piece slot *G'*, 15 and thus the breech-piece G and barrel end of the receiver C are united in a manner to subject the breech-piece to the rearward impact of the firing of the cartridge, so that the interlocked parts will recoil together.

20 The reverse or forward endwise motion of the hook with its rod and the rotative movement imparted to the device, whereby the parts assume their normal position, as represented in Figs. 7 and 8, is acquired in a 25 manner similar to its rearward and carriage-feeding movements hereinbefore described—that is to say, the device K 22 on the resumption of the receiver, spring-impelled, to its normal forward position, carries the hook 30 rod forward without the rotation of said rod because of the twist or cam engagement in the receiver-lug notch until the forward end of the hook-rod and hook encounter the end of the way or passage therefor in the frame, 35 whereupon the final portion of the receiver necessarily imparts rotative movement to the belt feed device, leaving it in readiness to engage in the next loop of the belt about concurrently with the withdrawal of the cartridge by the receiver-rib therefrom.

Immediately on the accomplishment of the locking of the head I of the breech-piece to the receiver, the lugs *h h*, coming to the straight portion *g' g'* of the breech-piece 45 slots, the firing-pin H quickly jumps forward, impelled by its spring M, and by means of its point, which passes through hole 12 in the breech-piece head I, explodes the cartridge in the barrel.

50 The immediate effect of this explosion is to cause the recoil of the barrel and attached receiver with its contained breech-piece and firing-pin rearward to the position shown in Figs. 14 and 25 of the drawings, the consequent important, but though very slight, rearward movement of the trip-rod therewith permitting the sear engagement of the firing-pin.

The before-described action of the hook-rod K again carries rearward a fresh cartridge, all as before described, and these movements are rapidly repeated so long as the pressure on the firing-button is continued, or the rapid firings may be intermitted and re-

sumed at will by releasings of and repeated 65 forward pressures on the firing-button.

Having thus described my invention, what I claim, and desire to secure by Letters Patent, is—

1. In a firearm of the character described, 70 the combination with the frame having a transverse cartridge-feedway and the barrel-receiver rearwardly and forwardly movable relatively to the frame, and provided with the cartridge-engaging rib, of a cartridge-belt feed device operable to bring the belt-carried cartridges successively to position to be engaged by said rib of the receiver, and means for actuating the belt feeding device. 75

2. In a firearm of the character described, 80 the combination with the frame having a transverse cartridge-feedway, having a chamber to the rear thereof and forwardly endwise connecting with said cartridge-feedway, and said chamber having an upper wall 85 downwardly and rearwardly inclined, of the barrel-receiver, endwise movable within the frame, having the upper and lower mortise-openings and having the cartridge-head-engaging rib. 90

3. In a firearm of the character described, 95 the combination with the frame having a transverse cartridge-feedway, having a chamber to the rear thereof and forwardly endwise connecting with said cartridge-feedway, and said chamber having an upper wall downwardly and rearwardly inclined, of the barrel-receiver, endwise movable within the frame, having the upper and lower mortise-openings and having the cartridge-head-engaging rib, and a device for feeding cartridges 100 successively transversely of the frame in said feedway to head engagement with said rib of the receiver. 105

4. In a firearm of the character described, 110 the combination with the frame having a transverse cartridge-feedway, having a chamber to the rear thereof and forwardly endwise connecting with said cartridge-feedway, and said chamber having an upper wall 115 downwardly and rearwardly inclined, of the barrel-receiver, endwise movable within the frame, having the upper and lower mortise-openings and having the cartridge-head-engaging rib, a spring forwardly reacting 120 against the receiver, and a cartridge-belt feeding device having endwise rearward and forwardly-returning movements in the frame, and also having an oscillatory movement, said feeding device being engaged with and actuated by the longitudinally-reciprocating receiver. 125

5. In a firearm of the character described, 130 the combination with the frame having a transverse cartridge-feedway, having a chamber to the rear thereof, forwardly endwise connecting with said feedway, and said chamber having an upper wall downwardly

- and rearwardly inclined, and having an opening thereunder through its lower portion, of the barrel-receiver, endwise movable within the frame having the upper and lower 5 mortise-openings and having the cartridge-head-engaging part, and a breech piece or bolt carried within and endwise movable relatively to the receiver, and provided with a cartridge-engaging head.
10. In a firearm of the character described, the combination with the frame constructed with the longitudinally-extended opening for the barrel-receiver, said opening having a closed top which is downwardly and rear- 15 wardly inclined, and said opening being continued downwardly through the lower portion of the frame, and said frame having a cartridge-introduction opening forward of the receiver-opening, with a chamber or passage 20 connecting said two openings, of the barrel-receiver, endwise movable within the frame, having the upper and lower openings and having a cartridge-head-engaging part, and a breech piece or bolt carried within and 25 endwise movable relatively to the receiver, and provided with a cartridge-engaging head.
7. In a firearm of the character described, the combination with the frame having an opening therein within which the barrel-re- 30 ceiver is capable of reciprocating movement, and having a wall above said opening rear-wardly and downwardly inclined, and having a cartridge-feedway forward of and communicating with said receiver-opening, of 35 the receiver having an opening from top to bottom therethrough, provided with a cartridge-head-engaging part at its forward portion and having a member extending from the rear of the vertical receiver-opening 40 formed with an under surface forwardly and upwardly inclined, for the purposes set forth.
8. In a firearm in combination, the frame having a transverse cartridge-belt feedway, therethrough, a device for engagement with the belt-loops for feeding the belt, recoil-ac- 45 tuated means for moving said device length- wise of the firearm for causing its engagement with, and disengagement from, the belt-loops and means for causing transverse swinging 50 movements for the crosswise feeding of the belt.
9. In a firearm, in combination, the frame having a transverse cartridge-belt feedway, the longitudinal rod endwise movable in the 55 frame, having an offset-belt-engaging member or hook, and said rod having, a spiral-cam formation, the receiver arranged for rearward movement by recoil within the frame, and having a member in engagement 60 with the spiral cam of said hook-rod, means for limiting the endwise motion of the hook-rod, and a spring forwardly reacting against the receiver.
10. In a firearm, in combination, the frame 65 having a transverse cartridge-belt feedway, the longitudinally-arranged rod endwise movable in the frame, having an offset-belt- 70 engaging hook, and said rod having, interme- diately of its length, the flat and spirally- winding opposite sides, the receiver to recoil within the frame having a radially-extending recessed lug within which said cam-faced intermediate portion of the hook-rod engages, means for limiting the endwise motions of the hook-rod, and a spring forwardly reacting 75 against the receiver.
11. In a firearm, in combination, the frame having a transverse cartridge-belt feedway and having a hook-rod bore with a commu- 80 nicating widened chamber at the forward end of said bore also communicating with said feedway, a longitudinally-arranged rod, shorter than said bore and adapted to move endwise therein, having an offset-belt-engag- 85 ing hook in said widened chamber, the re- ceiver to recoil within the frame, having a radially-extending member, and interengaging cam, and cam-engaging formations, appur- 90 tenant to the hook-rod and said receiver member, means for limiting the endwise movement of the hook-rod, and a spring for- 95 wardly effective on the receiver.
12. In a firearm, in combination, the frame having a transverse cartridge-belt feedway and having a hook-rod bore with a commu- 100 nicating widened chamber at the forward end of said bore, also communicating with said feedway, a longitudinally-arranged rod, shorter than said bore and adapted to move endwise therein, having an offset-belt-engag- 105 ing hook in said widened chamber, the re- ceiver to recoil within the frame, having a radially-extending member, and interengaging cam, and cam-engaging formations, appur- 110 tenant to the hook-rod and said receiver member, means for limiting the endwise movement of the hook-rod, a spring for- 115 wardly effective on the receiver, and a spring supported by the frame adjacent said car- 120 tridge-belt feedway, for engaging and pre- 125 venting a reversed movement of the belt.
13. In a firearm, in combination, the frame having a transverse cartridge-belt feedway and having a hook-rod bore with a commu- 130 nicating widened chamber at the forward end of said bore, also communicating with said feedway, a longitudinally-arranged rod, shorter than said bore and adapted to move endwise therein, having an offset-belt-engag- 135 ing hook in said widened chamber, the re- ceiver to recoil within the frame, having a radially-extending member, and interengaging cam, and cam-engaging formations, appur- 140 tenant to the hook-rod and said receiver mem- 145 ber, means for limiting the endwise move- 150 ments of the hook-rod, a spring forwardly ef- fective on the receiver, and a spring support- 155 ed by the frame within said widened cham- 160 ber for engaging the said hook.
14. In a firearm, in combination, the frame 165

having a transverse cartridge-belt feedway and having a hook-rod bore with a communicating widened chamber at the forward end of said bore also communicating with said feedway, a longitudinally-arranged rod, shorter than said bore and adapted to move endwise therein, having an offset-belt-engaging hook in said widened chamber, the receiver to recoil within the frame, having an upwardly-extending member provided with the sidewise-located cartridge-head-engaging rib.

15. In a firearm, in combination, the frame having a transverse cartridge-belt feedway and having a hook-rod bore with closing-walls of both ends thereof and a widened chamber at the forward end of said bore, a longitudinally-arranged rod, shorter than said bore and free for an endwise movement therein, having an offset-belt-engaging hook in said widened chamber, and said rod having a cam formation, the receiver to recoil within the frame having a radially-extending lug engaging said hook-rod cam, a spring encircling said hook-rod, rearwardly resisted, and having a forwardly-forcing engagement against said radially-extending lug of the receiver.

16. For a firearm of the character described, the feeding device consisting of a rod having at the forward end thereof, a return-bent formation and having intermediately a spirally-winding cam formation.

17. For a firearm of the character described, the barrel and barrel-receiver constructed with a cartridge-opening transversely therethrough and provided with a radially-extending member formed with the cartridge-head-engaging rib.

18. For a firearm of the character described, the barrel, and barrel-receiver constructed with a transverse cartridge-opening and with the longitudinal external rib having an upwardly and forwardly inclined cam-surface located above said cartridge-opening.

19. For a firearm of the character described, the barrel, and barrel-receiver having a transverse cartridge-opening and having the radial lug constructed with an endwise-opening notch therein, and provided with a sidewise-located cartridge-head-engaging rib.

20. For a firearm of the character described, the barrel-receiver constructed with the transverse cartridge-opening and having the outwardly-projecting longitudinally-arranged rib provided with the trip-rod-engaging shoulder 34.

21. For a firearm of the character described, the combination with the barrel-receiver having the transverse cartridge-aperture therethrough, the radially-extending lug 6 having on the side thereof the cartridge-head-engaging rib 76 and having the longitudinal external rib 7 with a forwardly and upwardly extending cam-surfaced portion thereof above said aperture.

22. In a firearm of the character described, the combination with the frame having a longitudinal barrel-receiver opening therein, of the barrel-receiver endwise movable within said opening, and having cartridge-apertures transversely therethrough constructed with locking-recesses 5, 5, the breech-piece fitted within and longitudinally movable relatively to the receiver, having a forward end head to engage in and disengage from the said locking-recesses, a firing-pin, endwise movable within, and relatively to, the breech-piece, having a rear-end head endwise movable relatively to the frame, but having a non-rotative engagement with the frame, and automatic means comprised in the breech-piece and firing-pin for imparting rotational movements to the breech-piece to lock it with and unlock it from the receiver.

23. In a recoil-gun, the combination with the barrel-receiver, and the breech-piece and firing-pin within the receiver, movable in unison, and also independently longitudinally movable each relatively to the other, the pivotally-mounted sear having a firing-pin-engaging member, of a firing-button, and a dog jointed to the sear and having an engagement with the firing-button to be moved longitudinally in unison therewith but free relatively to said firing-button for a movement relatively across the length thereof, and the trip-rod having rabbeted and prominent portions in proximity to said dog, and arranged to be engaged by the barrel-receiver for rearward and forward endwise movements in consonance with the recoil of the barrel, and the return forwardly to the normal position thereof.

24. In a firearm of the character described, the combination with the breech-piece, of the tubular firing-pin therein having a rear-end flange to be sear-engaged, the sear intermediately pivoted in a fixed rear portion of the firearm and having a forwardly-projecting firing-pin-engaging member, and having a member extended above the sear-pivot, the longitudinally-movable firing-button, the trip-rod automatically longitudinally rearwardly and forwardly movable, the dog forwardly jointed to the sear, interposed between the sear and trip-rod, in engagement with the firing-button, and said firing-button dog and trip-rod being constructed and arranged for the firing-button to control the position of the dog whereby it is subject either to firing-pin-releasing actuation or non-actuation by the trip-rod, for consequently assuring the release, or continued engagement of the sear by the firing-pin.

25. In a firearm of the character described, the combination with the frame having a longitudinal barrel-receiver opening therein, the barrel-receiver endwise movable rearwardly by recoil in said frame, a spring forwardly reacting on the receiver, of the breech-piece reacting on the receiver, of the breech-piece

- within and movable in unison with, and also movable independently of, said receiver, the tubular firing-pin therein having a rear-end flange to be sear-engaged, the sear intermediately pivoted in a fixed rear portion of the firearm and having a member extended above the sear-pivot, the longitudinally-movable firing-button, the trip-rod automatically longitudinally rearwardly and forwardly movable, the dog forwardly jointed to the sear, interposed between the sear and trip-rod, in engagement with the firing-button, and said firing-dog and trip-rod being constructed and arranged for the firing-button to control the position of the dog whereby it is subject either to firing-pin-releasing actuation or non-actuation by the trip-rod, for consequently assuring the release, or continued engagement of the sear by the firing-pin.
26. In a recoil-gun, the combination with the barrel-receiver, and the breech-piece and firing-pin within the receiver, movable in unison, and also independently longitudinally movable each relatively to the other, the pivotally-mounted sear having a firing-pin-engaging member, of a firing-button, and a dog jointed to the sear and having an engagement with the firing-button to be moved longitudinally in unison therewith but free relatively to said firing-button for a movement relatively across the length thereof, and the trip-rod having a rear-end flange or head in proximity to said dog, formed with the depression 63 having a forwardly-inclining wall, and said trip-rod arranged to be engaged by the barrel-receiver for rearward and forward endwise movements in consonance with the recoil of the barrel, and the return forwardly to the normal position thereof.
27. In a mechanism of the character described, the combination with the sear intermediately pivotally mounted, having a firing-pin-engaging member, and having a portion above its pivotal point constructed with a partially-circular recess, of the dog of approximately triangular form having a forwardly-rounded portion engaged in said sear-recess, the firing-button movable longitudinally of the firearm, and in engagement with the lower portion of said dog, and the trip-rod J forwardly and rearwardly movable and also co-operating with said dog.
28. In a mechanism of the character described, the combination with the sear intermediately pivotally mounted having a firing-pin-engaging member, of the dog of approximately triangular form having a forward portion jointed to an upper portion of said sear, the firing-button movable longitudinally of the firearm, and having a recess therein, within which the lower portion of said dog engages, and the trip-rod forwardly and rearwardly movable and also coacting with said dog.
29. In a mechanism of the character described, the combination with the sear intermediately pivotally mounted, having a firing-pin-engaging member, of the dog, of approximately triangular form, having a forward portion jointed to said sear, the firing-button movable longitudinally of the firearm, and made of tubular form, rearwardly closed and having the recess 66 within which a depending portion of said dog engages, and across the bore of which a depending portion of the sear protrudes, the spring interposed between the closed end of the firing-button and said depending portion of the sear, and the trip-rod forwardly and rearwardly movable and also co-operating with the rear portion of said dog.
30. In a mechanism of the character described, in combination, the sear comprising the sear-hook 55, the upwardly-extending portion having the approximately circular socket, and the depending member 52, the tubular firing-button, rearwardly endwise closed, and having through the upper wall thereof a recess through which the depending sear member extends, and having the recess 66 rearwardly therefrom, the spring 50 in compression between the closed end of the firing-button and the depending sear member and the dog of an approximately triangular form having forward rounded extremity engaged in said sear-socket and having its downwardly-extending portion engaging in the said recess 66.
31. In a recoil-operated firearm, the combination with the frame, and the barrel and receiver movable by recoil in the frame, of the breech-piece fitted in, and endwise movable relatively to, the receiver, the firing-pin fitted within and endwise movable relatively to the breech-piece, a spring forwardly reacting on the receiver, a spring forwardly reacting on the firing-pin, a device for engaging and disengaging the firing-pin, and a longitudinally-shiftable trip-rod, engaged and shifted by the reciprocating receiver, and coacting with the firing-pin-engaging device.
32. In a recoil-operated firearm, the combination with the frame, having a cartridge-way therein, and the barrel and receiver movable by recoil in the frame, and said receiver having the mortise-opening crosswise therethrough provided with the recesses 5, and the cam-rib 7 extending over said opening, and also having the lug 6 provided with the rib 76, of the breech-piece fitted in, and endwise movable relatively to, the receiver, and having a locking-head to engage with and disengage from the receiver, the firing-pin fitted within and endwise movable relatively to the breech-piece, a spring forwardly reacting on the receiver, a spring forwardly reacting on the firing-pin, a device for engaging and disengaging the firing-pin, means for actuating said firing-pin-engaging device, and means

for imparting locking and unlocking motions, independently of the longitudinal movements, to the breech-piece.

33. In a recoil-operated firearm, the combination with the frame, and the barrel and receiver movable by recoil in the frame, of the breech-piece fitted in and endwise movable relatively to the receiver, and having a locking-head to engage with and disengage from the receiver, the firing-pin fitted within and endwise movable relatively to the breech-piece, a spring forwardly reacting on the receiver, a spring forwardly reacting on the firing-pin, a sear for disengaging and engaging the firing-pin, a dog jointed to the sear, a firing-button with which said dog has an engagement, the trip-rod actuated forwardly and rearwardly by the receiver, and having rabbeted and prominent portions adjacent said dog, and means for imparting locking and unlocking motions, independently of its longitudinal movements, to the breech-piece.

34. In a recoil-operated gun, the combination with the frame, the barrel and receiver, movable in the frame by recoil, and constructed with locking-recess therein, and having a lug or projection 34, and a spring forwardly reacting on the receiver, of the breech-piece carried within the receiver and endwise movable relatively thereto, and having a part to engage said locking-recess, the firing-pin within the breech-piece and also endwise movable relatively thereto, a firing-pin-engaging mechanism, a trip-rod having forward and rearwardly located shoulders with which said receiver-lug alternately engages, and a firing-button coacting with said firing-pin-engaging mechanism for establishing coacting and non-coacting relations between the said mechanism and the trip-rod.

35. In a recoil-operated gun, the combination with the frame, the barrel and receiver, movable in the frame by recoil, and constructed with locking-recess therein, and having a lug or projection 34, and a spring forwardly reacting on the receiver, of the breech-piece carried within the receiver and endwise movable relatively thereto, and having a part to engage said locking-recess, the firing-pin within the breech-piece and also endwise movable relatively thereto, and said breech-piece and firing-pin having interengaging formations whereby the endwise movements of the one relatively to the other imparts successive rotative unlocking and locking movements of the breech-piece from and with the receiver, a firing-pin-engaging mechanism, a trip-rod having forward and rearwardly located shoulders with which said receiver-lug alternately engages, and a firing-button, coacting with said firing-pin-engaging mechanism for establishing coacting and non-coacting relations between the said mechanism and the trip-rod.

36. In a recoil-gun, the combination with the frame of the barrel-receiver, movable endwise relatively thereto, and a spring forwardly reacting thereon, of a rod engaging the receiver, arranged to be movable endwise in the frame for a distance as great as the receiver movement, and means for detachably locking said rod against having its full-length movements.

37. In a recoil-gun, the combination with the frame and receiver endwise movable thereon, and having a spring forwardly acting thereon, of the breech-piece and firing-pin within the receiver and movable relatively thereto, and to each other, in endwise directions, a firing-pin-engaging mechanism, a trip-rod actuated forwardly and rearwardly by the movements of the receiver and having a coacting relation with the firing-pin-engaging mechanism, means coacting with the trip-rod for limiting the movements thereof to comparatively short extents, said means being displaceable from engagement with said trip-rod whereby it may have a comparatively long endwise movement for initially setting the parts of the arm in their rearmost positions.

38. The combination with the frame and recoil-barrel receiver having the upstanding lug 34, of the breech-piece, firing-pin and firing-pin-engaging mechanism, the trip-rod J having the forwardly and rearwardly located shoulders 32 and 33, to be engaged by said receiver-lug, and having the separated shoulders forming the boundary of a recess, 39, and said trip-rod having the rear-end head constructed with recessed and prominent portions adjacent the firing-pin-engaging mechanism and a locking-bolt detachably engaging in said recess 39 and having a diameter less than the distance between the shoulder boundaries of said recess.

39. The trip-rod for inclusion in the arm, of the character described, having the shoulders 32 and 33, the recess 39, the rear-end head having in the forward face thereof a depression 63 with a forwardly-inclining surface.

40. In a firearm of the character described, the frame having a bore therethrough rearwardly opening and having at the rear end thereof the downwardly-opening recess constructed with the opposite inner side cuts or recesses 16, 16, in combination with the trip-rod J endwise movable in the frame, and having sidewise recess 39, the butt-piece adapted to engage in said downwardly-opening recess of the frame and having the opposite side ribs 18, 18, engaging in said recesses 16, and constructed with the upwardly-opening groove or recess 36, for the accommodation of the adjacent portion of the trip-rod and having in its wall a transverse socket with an outward opening therefrom, a bolt in said socket having a one-end engagement

in the trip-rod recess and a spring in said socket in endwise bearing against said bolt.

41. In a firearm, the combination with the frame, having a longitudinal receiver slide-way or chamber therein, formed with a rearwardly and downwardly inclined upper wall, having a bottom cartridge-shell-discharging opening, and having its lower wall adjacent the rear boundary of said opening formed with the rib 80, of the reciprocating barrel-receiver having a cartridge-head-engaging part, having the cartridge-opening from top to bottom therethrough, and provided with

the cam-rib 7 extending above its opening, and the breech-piece movable relatively to 15 the receiver and having, at its forward-end face, the cartridge-head-engaging ribs 9, 9, substantially as and for the purposes set forth.

Signed by me at Springfield, Massachusetts, in presence of two subscribing witnesses.
